UNITED STATES PATENT OFFICE

ALBERT L. HOWARD, OF BROCKTON, MASSACHUSETTS

DESIGN FOR A PIPING STRIP OR SIMILAR ARTICLE

Application filed November 8, 1930. Serial No. 37,591. Term of patent 14 years.

To all whom it may concern:

Be it known that I, ALBERT L. HOWARD, a citizen of the United States, residing at Brockton, in the county of Plymouth and Commonwealth of Massachusetts, have invented a new, original, and ornamental Design for a Piping Strip or Similar Article, of which the following is a specification, reference being had to the accompanying drawing, forming a part thereof.

The figure is a view in perspective of a portion of a piping strip of leather or the like, showing my new design.

I claim:

The ornamental design for a piping strip or similar article as shown.

ALBERT L. HOWARD.
